MARI ELIZE WOLVEKAMP, OF OAKLAND, CALIFORNIA.

INTERFERENCE TUBE FOR PHONOGRAHS AND TELEPHONES.

Application filed March 16, 1920. Serial No. 366,372.

To all whom it may concern:

Be it known that I, MARI ELIZE WOLVEKAMP, a subject of the Queen of the Netherlands, and a resident of Oakland, in the county of Alameda and State of California, have invented new and useful Improvements in Interference Tubes for Phonographs and Telephones, of which the following is a specification.

My invention relates to improvements in phonographs, but it consists more particularly in improvements in the sound conduit of phonographs, telephones, and the like, and it consists substantially in the construction and arrangement herein described and claimed.

The foremost object of the invention is to provide a tube to be fitted between the tone arm and reproducer of a phonograph, for the purpose of intercepting or interfering with certain undesirable high tones which ordinarily make their presence known by a high and often strong "whistle."

Other objects and advantages will appear in the following specification, reference being had to the accompanying drawing, in which:—

Figure 1 is a plan view illustrating the embodiment of the interference tubes in the tone arm of a phonograph,

Figure 2 is a horizontal section illustrating a slight modification wherein the large U tube is made extensible,

Figure 3 is a horizontal section illustrating how the branches on which the extensible U tube is fitted may be entirely closed by a stopper when desired,

Figure 4 is a detail cross section illustrating that the extensible U tube is made round,

Figure 5 is a detail cross section illustrating how it may be made oval in shape instead of round, and Figure 6 is a detail view of a modification wherein the interference tube is used in connection with a telephone receiver.

In carrying out my invention, I provide the main tube 1, which is of uniform diameter and is bent so as to provide a branch to which the sound reproducer R is fitted as at 2, and a branch to which the tone arm T is attached as at 3.

In the form of the invention in Figure 1, there are two interference tubes, the first consisting of the elbow 4 and the other of a U tube 5. Both of these are integral with the main tube 1 and are of precisely the same

diameter. There either may or may not be a division wall between the elbow 4 and the crook of the main tube 1, this being as desired, although Figures 2 and 3 show such a division wall.

In Figure 2 the U tube 5* is made extensible, short branches 6 being suitably fastened to the main tube 1 in place of the integral U tube 5 in Figure 1, on which branches the U tube 5* slides in and out, as is readily to be understood from Figure 2.

There may be occasions when it becomes desirable to discard the extensible U tube 5* altogether. In such event, a stopper consisting of a plate 7 with plugs 8 is fitted in place as in Figure 3. This stopper includes a ring 9 by which it is readily manipulated. The inner surfaces of the plugs 8 come exactly flush with the interior wall of the main tube 1, when the stopper is inserted as in Figure 3.

Instead of making the U tube 5 round, as in Figure 4, it may be made oval as in Figure 5, there being instances when this latter form is preferable in use to the former.

The advantages and operation, may be briefly pointed out to advantage. The underlying principle of this invention is to interfere with or eliminate certain undesirable sound waves, by allowing those waves to simultaneously traverse paths of different length so that they are totally eliminated so far as the resultant production is concerned.

The method employed, namely, the provision of the elbow 4 and U tube 5, enables the removal of the disagreeable tones, and mostly those that are high or metallic and which produce the disagreeable "whistle" that very often accompanies voices which are otherwise beautifully reproduced on the well known makes of records. This high whistling sound is estimated to be constituted of sound vibrations of approximately 2800 vibrations per second or of a wave length equal to about twice $2\frac{1}{2}$ inches.

It therefore necessarily follows that by providing a by-pass of approximately $2\frac{1}{2}$ inches longer, by the presence of the larger U-tube 5 in Figure 1, the false tones represented by the above whistling sound, are entirely eliminated and makes records producing them agreeable to hear. It may be found in actual practice that only the elbow 4 is required to produce the desired result, then again in other cases, it may be found necessary to employ the U-tube 5. Or in

still other cases, it may be found necessary to have the U-tube 5^a extensible. The use of these interference tubes makes the voice shorter, clearer and more distinct and very often more agreeable to hear, the slight actual reduction of loudness of the voice being of little consequence. The same idea, above expressed, may be applied with success to the receiver of a telephone, by connecting a horn of the receiver with a U-tube of equal diameter forming a by-pass for the sound.

It is desired to point out that the use of the interference tube is not confined to application to the tone arm of a phonograph because the interference tube may be employed in connection with a telephone receiver, as for example R in Figure 6. When used in this connection, the interference tube 1^a performs precisely the same function that it performs when used in a tone arm, namely, eliminates the high or false and objectionable tones that often are so piercing to the ear of the listener. It is shown as simply inserted in the outlet of the receiver on front of the diaphragm d, the U-tube 5^b being of precisely the same arrangement as that in Figure 1.

While the construction and arrangement of the tone interference tubes as herein de-

scribed and claimed, is that of a generally preferred form, obviously modifications and changes can be made without departing from the spirit of the invention or the scope of the claims.

I claim:—

1. In combination with the reproducer and with the tone arm of a phonograph, a relatively narrow main sound conduit including by-pass means the ends of which are close together and communicate with said sound conduit, permitting two large and substantially equal volumes of sound to simultaneously traverse paths of distinctly different lengths which are not varied by the movement of the phonograph, eliminating by interference a high or false tone.

2. In combination with the reproducer and with the tone arm of a phonograph, a relatively narrow main sound conduit provided with two lateral openings close together and communicating with both ends of a U-tube, permitting two large and substantially equal volumes of sound to simultaneously traverse paths of distinctly different lengths which are not varied by the movement of the phonograph, eliminating by interference a high or false tone.

MARI ELIZE WOLVEKAMP.
